(57) **CLAIM**

The ornamental design for a protective valve cap, as shown and described.

DESCRIPTION

FIG. 1 is a perspective side view of a first embodiment of the protective valve cap looking into the cap;

FIG. 2 is a side view thereof, the opposite side view being a mirror image;

FIG. 3 is a front view thereof;

FIG. 4 is a rear view thereof;

FIG. 5 is a top view thereof;

FIG. 6 is a bottom view thereof;

FIG. 7 is a cross-sectional view thereof, taken along the lines 7—7 of FIG. 5;

FIG. 8 is a top view thereof mounted on a valve stem;

FIG. 9 is a side view thereof mounted on a valve stem;

FIG. 10 is a cross-sectional view taken along the lines 10—10 of FIG. 8;

FIG. 11 is a top view of a second embodiment of a protective valve cap;

FIG. 12 is a perspective side view thereof looking into the cap;

FIG. 13 is a side view thereof;

FIG. 14 is a front view thereof, the rear view being the same as FIG. 4; and,

FIG. 15 is a bottom view thereof.

The broken line showing is for illustrative purposes only and does not form part of the claimed design.
